PATTERN CONTROL ARRANGEMENT FOR A
CIRCULAR KNITTING MACHINE

Johann Albrecht Schaefer, Merzhausen, near Freiburg im Breisgau, and Richard Schmidt, Stuttgart-Vaihingen, Germany, assignors to Firma Franz Morat K.G., Stuttgart-Vaihingen, Germany

Filed Dec. 21, 1960, Ser. No. 77,389

Claims priority, application Germany July 16, 1956
20 Claims. (Cl. 66—50)

The present invention relates to a pattern control arrangement for knitting machines, and more particularly to an electrically controlled pattern wheel in which the jacks are set in accordance with a selectable pattern by electric impulses.

The present invention is a continuation-in-part application of my co-pending application entitled "Pattern Control Arrangement for Circular Knitting Machines and the Like," Serial No. 671,928, filed on July 15, 1957, and now abandoned.

With circular knitting machines there are a plurality of operating stations distributed about the axis of the machine and a pattern wheel is located at each operating station. These pattern wheels form assemblies which influence the needles of the rotating needle cylinder so as to provide the most varied patterns in the work.

Such a pattern wheel has an annular toothed periphery and the teeth of the periphery of the pattern wheel extend into the spaces between adjacent needle butts so that during rotation of the needle cylinder the pattern wheel will also turn since the teeth at the outer periphery of the pattern wheel in effect mesh with the needles. In the spaces between its teeth, the pattern wheel is provided with a plurality of grooves distributed about its axis and needle-influencing jacks are respectively shiftable in these grooves and engage with their upper edges the butts of the needles so as to raise the latter and thus make a predetermined pattern. The turning axis of the pattern wheel is inclined with respect to the turning axis of the needle cylinder and as a result of the inclination between these axes, the needle butts which are engaged by the jacks of the pattern wheel will be raised during the turning of the needle cylinder and pattern wheel.

In order to raise the needles of the needle cylinder according to a predetermined program so as to provide a desired pattern, the jacks must be arranged on the pattern wheel in a predetermined manner.

The jacks which are in the form of thin steel plates are conventionally located in the grooves of the pattern wheel and are fixed thereto by a cover which is fixed to the pattern wheel and engages the jacks to maintain the latter on the pattern wheel. In order to change the arrangement of the jacks on a given pattern wheel it is necessary to remove the pattern wheel from its support and, after removal of the cover, the jacks are rearranged according to the new pattern, whereupon the cover is replaced and the pattern wheel is again placed on its rotatable support.

At the present time it is not possible to change the positions of the jacks on a pattern wheel while the knitting machine is operating. Thus, it is not possible with known pattern arrangements to change the pattern while a course is being knitted or to change a pattern during the knitting of an elongated tube of fabric. It is possible to change the pattern from course to course by having different pattern wheels operate on the different courses, the pattern wheels at the different operating stations having different arrangements of their jacks. However, with this arrangement it is only possible to distribute a pattern over a predetermined number of courses, this number being equal to the number of pattern wheels and to the number of operating stations. For example, if a circular knitting machine has six operating stations with six pattern wheels

2

respectively located at these stations, then each of six successive courses may differently be patterned. However after the knitting of six courses it is necessary to repeat the pattern of the first course.

It is not possible with the known patterning arrangements to stop the operation of the pattern wheel while the knitting machine operates so as to knit an unpatterned portion for a controlled length of time and then to again start the operation of the pattern wheel, and it is also not possible to continuously change the arrangement of the jacks on the pattern wheel during operation of the knitting machine.

It is thus apparent that with the present state of the art the patterning possibilities are greatly limited not only with respect to the patterning itself but also with respect to stopping and starting of the patterning operations while the knitting machine operates.

One of the objects of the present invention is to overcome the above drawbacks by providing a patterning arrangement for circular knitting machines or the like and capable of having the arrangement of its needle-influencing jacks changed at will during the operation of the knitting machine.

It is also an object of the present invention to provide a patterning arrangement which enables the pattern of a single pattern wheel to be continuously changed so that no pattern has to be repeated during each revolution of the pattern wheel.

Another object of the present invention is to provide a patterning arrangement capable of being reset during operation of the knitting machine in any selected fashion with a structure which is exceedingly simple and reliable in operation.

An additional object of the present invention is to provide a jack-selecting arrangement which is electrically operated and which has electromagnets small enough to operate in an extremely short period of time.

A further object of the present invention is to provide a patterning arrangement wherein the selection of the pattern is electromagnetically controlled but wherein the main part of the movement of the jacks is brought about mechanically and the jacks are mechanically held in operative position.

With the above objects in view, the present invention mainly consists of a patterning arrangement for circular knitting machines or the like: According to one embodiment, this arrangement includes a support means and a carrier means rotatably carried by said support means. This carrier means carries needle-influencing elements, hereinafter called "jacks," and supports the same for movement between inoperative and operating positions, the needle-influencing elements in their operating positions shifting the needles to produce a desired pattern during rotation of the carrier means. An electromagnetic control means is located adjacent the carrier means for acting directly or indirectly on the jacks during rotation of the carrier means to cause selected jacks to at least start to move toward their operating positions.

In accordance with the preferred embodiment of the present invention, stationary cam means are provided which have a gap opposite the electromagnetic control means, and when each jack passes the gap, an associated moving element, preferably in the form of a springy member, is controlled by the action of the electromagnetic means to either pass through the gap to effect shifting of the associated jack to an operating position, or to further proceed along the cam means in an inoperative position.

Additional cam means are provided for returning to the inoperative position those jacks which were advanced to the operating position so that for each revolution of the pattern wheel, a new pattern may be selected.

In one embodiment of the invention, the electromagnetic means controls a blocking lever which is movable between a gap-closing position, and a retracted position permitting passage of springy members through the gap, such springy members being in tensioned condition when arriving at the gap due to the action of cam means. In another embodiment of the invention, the electromagnetic means acts on springy wires to move the same through the gap to an intermediate position from which they are moved to an end position when passing along a control cam surface, and in such end position of the springy members, correlated jacks are pushed by the same to the operating position.

In a further embodiment of the invention, two electromagnetic means are provided on opposite sides of the gap. One electromagnetic means, when energized, causes the jacks passing the gap to remain in the inoperative position, while the other electromagnetic means, when energized, causes the jacks to pass to the operating position.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a fragmentary side view of a pattern wheel according to the present invention, mainly shown in section along line I—I in FIG. 2;

FIG. 2 is a top view of the pattern wheel shown in FIG. 1 with the cover plate omitted;

FIG. 3 is a fragmentary sectional view of the pattern wheel of FIG. 1, the section being taken on line III—III in FIG. 2;

FIG. 4 is a fragmentary sectional view taken on line IV—IV in FIG. 2;

FIG. 5 is a fragmentary sectional view taken on line V—V in FIG. 2;

FIG. 6 is a fragmentary sectional view taken on line VI—VI in FIG. 2;

FIG. 7 is a fragmentary sectional view taken on line VII—VII in FIG. 2;

FIG. 8 is a fragmentary side elevation illustrating a jack in its operating position;

FIG. 9 is a fragmentary sectional view of a pattern wheel according to a modified embodiment of the present invention, the section being taken on line IX—IX in FIG. 10;

FIG. 10 is a fragmentary top view of the pattern wheel shown in FIG. 9;

FIG. 11 is a fragmentary cross-sectional view corresponding to FIG. 9 but illustrating another modified embodiment of the invention;

FIG. 12 is a fragmentary side elevation of a detail of the embodiment of FIG. 9; and

FIG. 13 is a fragmentary schematic plan view illustrating the operation of the embodiment of FIG. 7.

Referring now to the embodiment illustrated in FIGS. 1 to 8, as best seen in FIGS. 1 and 3, the support of the pattern wheel includes a part 104a with an oblique face, a support plate 104, and shaft portion 4 having a threaded portion onto which the threaded bore 5a of a cover plate is screwed. The edge of the circular plate 104 projects beyond the other parts of the device in order to protect the jacks, but at an operating station A, see FIG. 2, the periphery of plate 104 is cut off along a chord 104b to facilitate the operation of the jacks on the cylinder needles of the knitting machine. The oblique face of member 104a permits the mounting of shaft 4 in a position inclined to the axis of rotation of the needle cylinder.

The pattern wheel proper is mounted for rotation on shaft portion 4, and includes a carrier means having a

tubular bushing 3a surrounding shaft 4, a floor portion 3, and a clamping ring 7 which is secured by screws 7a to the floor portion 3.

The outer periphery of the floor portion 3 has radial slots defining teeth 1 which extend into the spaces between the shanks of the needles of needle cylinder of the circular knitting machine, so that when the needle cylinder rotates, the pattern wheel also rotates about shaft 4.

10 The floor portion 3 of the pattern wheel is formed in its upper face with a plurality of radial grooves 3b respectively receiving the jacks 2 which are in the form of thin plates having butts 2', and projecting portions 2" which cooperate with the butts 130a of the cylinder needles 130, as shown in FIG. 8. However, it will be understood that jacks 2 only cooperate with the cylinder needles 130, if the jacks are in an advanced operating position. Jacks 2 in operating position control the needles to knit in accordance with the pattern selected by placing selected jacks in the advanced operating position. Jacks 2 are shiftable through a relatively short distance in the radial grooves 3b between an inner inoperative position and an outer operating position.

15 A plurality of springy members in the form of angular wires 6 are clamped to the pattern wheel. The springy wire members 6 have legs 6a which are disposed on the recessed surface 3c of the floor portion 3, and are clamped to the same by the ring 7. The other legs 6b are respectively located in grooves 3b so that each springy member 6 cooperates with the butt 2' of the jack 2 located in the same groove 3b. The legs 6b have free end portions 6c projecting beyond the butts 2'.

20 As shown in FIG. 4, the legs 6a and 6b extend substantially at right angles to each other when springy members 6 are not tensioned.

25 The free end portions 6c of the springy members 6 are located in the region of cam means 8 and 9 which are fixed to the underside of the stationary cover 5. Since the pattern wheel turns with springy members 6, legs 6b will move relative to cam 9 until the end portions 6c engage the cam surface 9a and are inwardly bent so that legs 6b assume the position shown in FIG. 5 in which the springy members 6 are tensioned since legs 6b tend to return to the untensioned position shown in FIG. 4.

30 The end 9c of cam 9, which is also the end of cam surface 9a, defines with the end 8' of cam 8, a gap 10 which has a width slightly greater than the thickness of leg portion 6c to permit portion 6c to pass through gap 10 and to assume again the untensioned position of FIG. 4. However, a blocking lever 12 closes gap 10 in the position shown in solid lines in FIG. 2 so that the end portions 6c can only move through gap 10 if lever 12 is 35 moved to the position shown in broken lines in FIG. 2, as will be described hereinafter in greater detail.

35 Those end portions 6c which have passed through gap 10 will be engaged by the cam surface 8b of cam 8, as shown in FIG. 6. Cam surface 8b rises gradually so that legs 6b are further displaced while moving along cam surface 8b to the operating station A. Legs 6b act on the butts of jacks 2, so that the same are shifted to the advanced operating position as shown in FIG. 6 in which they may act on the cylinder needles 130, as shown 40 in FIG. 8. Further turning movement of the pattern wheel will bring the end portion 6c of each operative springy member 6 to the point 8k of cam 8 where the legs 6b are free to return to the untensioned position shown in FIG. 4. During further turning movement of the pattern wheel, and shortly before reaching gap 10, end portion 6c will again engage cam surface 9a and be tensioned, as explained with reference to FIG. 5.

45 Those end portions 6c which are prevented by the blocking portion 12a of blocking lever 12 to pass through gap 10, slide from blocking portion 12a onto the inner

cam surface $8a$ where they are permitted to return to the untensioned position, as shown in FIG. 7. After the end point $8k$ of cam 8 , all springy members are in the untensioned position shown in FIG. 4, and all springy members are tensioned by cam surface $9a$ shortly before reaching gap 10 .

A ring member 14 is secured to cover 4 , and has a lower portion slidably guiding jacks 2 . Blocking lever 12 is mounted on ring member 14 for turning movement about a pivot 11 which is screwed into a portion of ring member 14 . Lever 12 is angular, and its blocking portion $12a$ is curved so that it is movable past the rear face of cam 9 between the blocking position closing gap 10 , and the inoperative position shown in broken lines in FIG. 2. As best seen in FIG. 3, a pin 13 is secured to blocking lever 12 , and projects through a slot $5a$ in cover 5 . A coil spring 131 is secured to a hook $13a$ on pin 13 , and also to a small bracket 132 which is secured by screw $132a$ to cover 5 . Spring 131 biases lever 12 to assume the position in which the gap 10 is open for passage of the end portions $6c$ of the springy member 6 . An electromagnet including pole shoes 133 and 134 , and a winding 135 is mounted by screws 136 on a bracket 137 which is secured by screws 138 to cover 5 . The pole shoes 133 , 134 have points located directly opposite pin 13 so that the pin is attracted when winding 135 is energized, and moves together with blocking lever 12 to the position in which blocking portion $12a$ of blocking lever 12 closes gap 10 .

The pattern wheel arrangement shown in FIGS. 1 to 8 operates in the following manner: When the needle cylinder of the circular knitting machine rotates, the pattern wheel also rotates due to the meshing engagement between the teeth 1 with the needles 130 of the needle cylinder. The thickness and the pitch of teeth 1 are chosen in accordance with the dimensions of the needle cylinder. During rotation of the pattern wheel in the direction of the arrow X in FIG. 2, the jacks 2 and the springy members 6 arrive in the region of cam 9 . The legs $6b$ of the springy members are untensioned. The jacks 2 are either in advanced operating position, or in retracted inoperative position. Those jacks 2 which are in the advanced operating positions, engage with their butts $2'$ the cam surface $9b$ of cam 9 and are gradually shifted to the retracted inoperative position shown in FIG. 5 before arriving in the region of the gap 10 . At the same time, all springy members approaching the gap 10 are tensioned, as shown in FIG. 5. As the springy members successively arrive at gap 10 , the winding 135 of the electromagnet receives either a control impulse and is energized, or remains de-energized.

If the electromagnet is de-energized, the end portion $6c$ of leg $6b$ of the respective springy member can pass through the gap to be engaged by the gradually rising cam surface $8b$ which shifts leg $6b$ to the tensioned position shown in FIG. 6 in which leg $6b$ engages butt $2'$ of jack 2 associated therewith so that jack 2 is shifted to the operating position in which it cooperates with a butt $130a$ of a cylinder needle 30 to raise the same.

If the electromagnet receives a control impulse at the moment in which another springy member 6 passes the gap, the gap 10 is closed, and the respective end portion $6c$ is engaged by the inner cam surface $8a$, as shown in FIG. 7 and passes along the same until it reaches point $8k$ of cam 8 . Springy members 6 which are restrained by blocking portion $12a$ and cam surface $8a$, have no influence on the associated jacks, so that the same remain in the inoperative position.

It will be noted that the arrangement of blocking lever 12 is such that it has to turn through a very small angle to close or open, respectively, gap 10 . In circular knitting machines of the type to which the present invention relates, it is important that the jacks are operated in an extremely short period of time. Thus, it is not possible to have a very large electromagnet operating

on lever 12 . A large electromagnet requires a longer time for energizing and de-energizing, so that it could not operate at the high frequency required for controlling the springy members 6 during rotation of the pattern wheel. Since lever 12 is relatively small and light, and moves only through a very short distance, a small electromagnet can be used, which is rapidly energized and de-energized within the available short period of time.

In the embodiment of FIGS. 1 to 3, the electromagnet indirectly controls the springy members 6 through lever 12 . In the embodiment illustrated in FIGS. 9 and 10, the electromagnet acts directly on the springy members 6 so that the electromagnet requires even less power in the embodiment of FIGS. 9 and 10 than in the embodiment of FIGS. 1 to 3 and in this manner an even faster operation is possible. The same reference numerals are used in the following description of modified embodiments to designate elements corresponding to elements in FIGS. 1 to 3.

10 The springy members 6 of FIGS. 9 and 10 are identical with those of FIG. 1 and have free end portions $6c$. The pattern wheel itself as well as the cover 5 and the teeth 1 and jacks 2 are all identical with those of FIG. 1. The cover 5 of FIG. 9 fixedly carries at its underside a cam $9'$ having a cam surface $9a$ for guiding the end portions $6c$ of springy members 6 to the position shown in FIG. 5 in which the legs $6b$ are tensioned. In the same way as in FIGS. 1 and 2, an end $9c$ of the cam $9'$ defines with the end $8'$ of a cam 8 the gap 10 beneath the cover 5 through which the free ends $6c$ of selected springy members 6 are movable. The cam 8 of FIGS. 9 and 10 is identical with cam 8 of FIGS. 1 and 2, and FIG. 10 clearly shows the end $8k$ of the cam 8 distant from the gap 10 . Thus, when a free end portion $6c$ of a springy member 6 moves through the gap 10 to an intermediate position, it is engaged by the outer rising cam surface $8b$ of the cam 8 so as to be moved away from the axis of rotation of the pattern wheel to an end position as shown in FIG. 6 in which the jacks 2 are moved to their operating position by legs $6b$. It will be noted from the positions of the ends $8'$ and $9c$ of cams 8 and $9'$ with respect to each other that only an extremely small radial movement of each end $6c$ of the springy members 6 is required in order to cause these springy members to move to the intermediate position and to come into engagement with the outer rising surface $8b$ of the cam 8 . The jacks indicated with the reference characters $2a$ are located at their operating positions at the operating station A. It will be noted that the outer surface $8b$ gradually approaches the axis of rotation of the pattern wheel in a clockwise direction beyond the operating station A until the end $8k$ of the cam is reached, and when the springy members 6 turn beyond the end $8k$ of the cam 8 they are in their unstressed initial position shown in FIG. 4.

15 20 25 30 35 40 45 50 55 60 65 70 75 The inner arcuate surface $8a$ holds the springy members 6 which have not passed through gap 10 during rotation of the pattern wheel.

Cam $9'$ has a second cam surface $9b$ engaging the butts $2'$ of the jacks 2 so as to move those jacks 2 which have been placed in their operating positions back to their inoperative position before the jacks 2 arrive at the selecting station shown at the left of FIG. 10 where the gap 10 is located. The cam surface $9b$ is shaped so as to gradually move the jacks 2 radially inwardly toward their inoperative positions so that all jacks are back in their inoperative positions when they reach the selecting station.

The cover 5 of FIGS. 9 and 10 is formed with an opening in which an electromagnet 16 is located, and a suitable bracket $16a$ is fixed to the top face of the cover 5 and carries the electromagnet 16 in the manner shown in FIG. 9. The electromagnet includes a pole shoe 17 which is located closely adjacent to the gap 10 between the latter and the axis of rotation of the pattern

wheel. The distance between the pole shoe 17 and the gap 10 is slightly greater than the thickness of the springy wire members 6, and the legs 6b pass along cam surface 9a to the region of pole shoe 17 as shown in FIG. 10. When the electromagnet 16 is energized, it attracts and holds back the springy free leg portions 6b of the springy members 6 as they move by the gap 10 and prevent the end portions 6c from moving through the gap 10. Thus, those spring members 6 which are acted on by the electromagnet 16, 17 will not engage their corresponding jacks to move the latter outwardly to their operating positions. When the electromagnet 16 is not energized, nothing stops the springy legs 6b from moving with their free end portions 6c through the gap 10, and the springy end portions 6c of the members 6 released by cam surface 9a at the gap 10 will move therethrough so as to engage the outer arcuate rising face 8b of the cam 8 on which they are guided to an advanced position, as shown in FIG. 6, to move their corresponding jacks outwardly to their operating positions.

Where the electromagnetic force required by the structure is so great that a single electromagnet will be of such a size that it cannot be operated with the desired frequency, then in accordance with the present invention a plurality of small electromagnets may be used so that their total force provides the required power and at the same time these small magnets may be energized with the necessary frequency.

Of course, the invention is equally applicable to pattern arrangements where the carrier means instead of taking the form of a carrier wheel having radial grooves as described above takes the form of a rotating carrier structure which supports the jacks for axial shifting movement between their operating and inoperative positions, or the arrangement may be such that the jacks are pivotally carried by the carrier means for turning movement with respect to the latter between their operating and inoperative positions. Also, the jacks, instead of taking the form of plates may take the form of pins.

In stead of providing a cam 9b which acts on butts of the jacks to return the latter from their operating to their inoperative positions, a second electromagnet may be provided to act on the jacks in order to return the latter to their inoperative positions after they move beyond the operating station A.

In the above-described structure the electromagnetic means 16, 17 operates indirectly on the jacks. It is also possible to provide an arrangement where the electromagnetic means acts directly on the jacks. The jacks must be moved through a distance on the order of 3-5 mm. between their inoperative and operating positions. Where a single magnet is used to move a jack all the way through this distance, a relatively large amount of power is required since the movement of the jacks must take place in an extremely short period of time. For example, in a circular knitting machine which as 1560 needles and which turns at a rate of 20 revolution per minute it is necessary for a jack to be moved from its inoperative to its operating position in 0.002 second. Thus, at the selecting station the magnet is required to effect movement of a jack to its operating position in this extremely small period of time. A magnet which is capable of moving a jack through the entire distance to its operating position would have be of such a size that it is not possible for it to be energized or deenergized within the extremely small period of time made necessary by the other factors.

It is, however, possible to provide at the selecting station a small magnet which directly acts on the jacks to initiate the movement of each jack toward its operating position. The magnet may move the selected jacks through only a relatively small fraction of the total distance required, and then the butt 2' of the jack 2 will come into engagement with a cam similar to cam 8 at the outer face 8b thereof so as to be moved in this way

5 by a purely mechanical means through the remainder of the distance necessary for placing the jack in its operating position. Thus, an electromagnet may act directly on the jacks without the intermediary of springy members 6, and at the same time can be small enough to respond to the impulses with the desired frequency simply by only initiating the movement of the jack which after it has been moved to a slight distance from its inoperative position comes into engagement with suitable cam means which effect the movement of a selected jack to its operating position and the return of the jack to its inoperative position.

10 It should be noted that with an arrangement as described above in connection with FIGS. 9 and 10 the power requirement of the magnet is so small that it is easily possible to operate the magnet at a frequency which is much greater than that which is required by the speed of the machine.

15 As shown in FIGS. 11, 12 and 13, instead of providing springy members in the form of wires 6 to act on the needle-influencing jacks, it is also possible to provide rigid members 60b which are pivotally carried by pins 60a clamped by a clamping ring 7 of the pattern wheel respectively next to the inner ends of the 20 associated jacks 2 and which are capable of being turned so that these members 60b engage the jacks 2 along the entire height of their inner ends 2' to move the jacks 2 outwardly to their operating positions. Suitable wire pins 60a may be carried by the pattern wheel in order to pivotally support the pivoted jack moving members 60b of such an arrangement. Such jack moving members 60b are located in the same grooves 3b in which the jacks 2 are located in order to engage the inner ends 2' of the latter, and these inner ends are suitably 25 shaped so as to have a good contact with tongue-like moving members 60b. These tongue-like moving members 60b are provided with end portions 60c in association with cam means 8, 9" of the type described above as schematically shown in FIG. 13, and the movement 30 of the jacks is controlled depending upon whether or not the jack-moving members 60b, 60c move through the gap 10. At the gap 10 a magnet 16a, 17a is located which, when energized, acts on portions 60c of these moving members 60b to prevent the latter from turning 35 through the gap 10, and a second magnet 116a, 117a is also located at the gap 10 at the opposite side thereof from the first magnet 16a, 17a and acts in opposition to the latter so that when the second magnet 116a is energized, the jack-moving members 60b, 60c will be 40 moved through the gap 10 to engage the jacks 2 for moving the latter to their operating position. The first magnet 16a, 17a which acts on the pivotally supported jack moving members 60b so that they do not move through the gap 10 is located adjacent the gap 10 between the latter and the axis of rotation of the pattern wheel, while the second magnet 116a, 116b which moves the jack moving members 60b, 60c through the gap, is located adjacent the gap but on the side thereof remote from the axis of rotation of the pattern wheel.

45 Any suitable known programming means may be provided for controlling the moments when the electromagnets are energized in any of the above-described embodiments of the invention. Thus, a Jacquard device may be used for this purpose, or any roll or band having the necessary pattern information registered thereon may be used. For example, impulses may be set into a magnetic tape which moves past a suitable head which senses the impulses and energizes and deenergizes the electromagnets accordingly, or a card or roll of papers or the like may be punched with suitable holes and a photoelectric arrangement may be provided according to which a beam of light when it passes through an opening of the card or band energizes the electromagnet.

50 It will be understood that each of the elements described above, or two or more together, may also find

a useful application in other types of pattern wheels differing from the types described above.

The invention has been illustrated and described as embodied in electrically controlled patterning arrangements for circular knitting machines, but is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a patterning arrangement for a circular knitting machine, in combination, support means; carrier means rotatably carried by said support means; a plurality of needle-influencing elements carried by said carrier means for rotation therewith and mounted on the same for movement between an inoperative position and an operating position; a plurality of moving members carried by said carrier means for rotation therewith and being at least partly movable in radial direction with respect to the axis of rotation of said carrier means from an inner position through an intermediate position to an outer end position, said moving members being respectively operatively connected with said needle-influencing elements for successively moving the same to said operating position thereof; cam means fixedly mounted on said support means and located adjacent said carrier means, said cam means including a first arcuate cam and a second arcuate cam, said first and second cams defining a gap between each other, said movable members sliding along said first cam during rotation of said carrier means and being held by the same in said inner position when arriving at said gap and then sliding along said second cam, said second cam having an inner arcuate cam surface for engaging said moving members in said inner position, and an outer arcuate cam surface having a first face portion adjacent said gap for engaging movable members in said intermediate position and a second face portion for guiding moving members to said outer end position; so that the respective correlated needle-influencing elements are moved to the operating positions thereof; electro-magnetic means located adjacent said gap and operatively connected to movable members passing said gap to cause movement of selected movable members through said gap to said intermediate position so that the selected moving members are engaged by said outer cam surface and moved to said outer end position while non-selected moving members are engaged by said inner cam surface and remain in said inner position; and return cam means disposed on said support means in the region of said first cam for engaging needle-influencing elements in said operating positions and for moving the same to said inoperative position before said needle-influencing elements and the respective correlated moving elements arrive at said gap during rotation of said carrier means.

2. In a patterning arrangement for a circular knitting machine, in combination, support means; carrier means rotatably carried by said support means; a plurality of needle-influencing elements carried by said carrier means for rotation therewith and mounted on the same for movement between an inoperative position and an operating position; a plurality of springy moving members carried by said carrier means for rotation therewith and being partly movable in radial direction with respect to the axis of rotation of said carrier means from an inner tensioned position through an intermediate position to an

outer end position, said moving members being respectively operatively connected with said needle-influencing elements for successively moving the same to said operating position thereof; cam means fixedly mounted on said support means and located adjacent said carrier means, said cam means including a first arcuate cam and a second arcuate cam, said first and second cams defining a gap between each other, said movable members sliding along said first cam during rotation of said carrier means and being moved by the same to said inner tensioned position when arriving at said gap and then sliding along said second cam, said second cam having an inner arcuate cam surface for engaging said moving members in said inner position, and an outer arcuate cam surface having a first face portion adjacent said gap for engaging movable members in said intermediate position and a second face portion for guiding moving members to said outer end position; so that the respective correlated needle-influencing elements are moved to the operating positions thereof; electro-magnetic means located adjacent said gap outwardly of the same and of said outer cam surface, and including a movable blocking member having a first position located in said gap for closing the same and a second position retracted from said gap so that said movable members move onto said inner cam surface in said first position of said blocking member and resiliently pass through said gap to said intermediate position in said second position of said blocking member to be engaged by said outer cam surface so that the selected moving members are engaged by said outer cam surface and moved to said outer end position while non-selected moving members are engaged by said inner cam surface and remain in said inner position; and return cam means disposed on said support means in the region of said first cam for engaging needle-influencing elements in said operating positions and for moving the same to said inoperative position before said needle-influencing elements and the respective correlated moving elements arrive at said gap during rotation of said carrier means.

3. An arrangement as set forth in claim 2 wherein said blocking member is a blocking lever turnably mounted on said support means for movement between said first and second positions, and including spring means operatively connected to said blocking lever for moving the same to said second position, said blocking lever moving to said first position when said electro-magnetic means is energized.

4. In a patterning arrangement for a circular knitting machine, in combination, support means; carrier means rotatably carried by said support means; a plurality of needle-influencing elements carried by said carrier means for rotation therewith and mounted on the same for movement between an inoperative position and an operating position; a plurality of springy moving members carried by said carrier means for rotation therewith and being partly movable in radial direction with respect to the axis of rotation of said carrier means from an inner tensioned position through an intermediate position to an outer end position, said moving members being respectively operatively connected with said needle-influencing elements for successively moving the same to said operating position thereof; cam means fixedly mounted on said support means and located adjacent said carrier means, said cam means including a first arcuate cam and a second arcuate cam, said first and second cams defining a gap between each other, said movable members sliding along said first cam during rotation of said carrier means and being moved by the same to said inner tensioned position when arriving at said gap and then sliding along said second cam, said second cam having an inner arcuate cam surface for engaging said moving members in said inner position, and an outer arcuate cam surface having a first face portion adjacent said gap for engaging movable members in said intermediate position and a second face portion for guiding moving members to said outer end

position so that the respective correlated needle-influencing elements are moved to the operating positions thereof; electro-magnetic means located adjacent said gap inwardly of the same and of said inner cam surface and magnetically connected to springy members passing said gap and permitting in de-energized condition selected springy members to pass through said gap and to resiliently assume said intermediate position, and attracting non-selected movable members to hold the same in said inner tensioned position until the same have passed beyond the gap and onto said inner cam surface so that the selected moving members are engaged by said outer cam surface and moved to said outer end position while non-selected moving members are engaged by said inner cam surface and remain in said inner position; and return cam means disposed on said support means in the region of said first cam for engaging needle-influencing elements in said operating positions and for moving the same to said inoperative position before said needle-influencing elements and the respective correlated moving elements arrive at said gap during rotation of said carrier means.

5. An arrangement as set forth in claim 4 wherein said springy members are angular and have a first leg secured to said carrier means, and a second leg engaging the inner end of the correlated needle-influencing element and terminating in an end portion located at the level of said cam means for sliding along said cam surfaces, and wherein said springy members are untensioned in said intermediate position, and resiliently tensioned in said inner position and in said outer end position so that said springy members return to said intermediate position when passing beyond the end of said second face portion of said outer cam surface.

6. In a patterning arrangement for a circular knitting machine, in combination, support means; carrier means rotatably carried by said support means; a plurality of needle-influencing elements carried by said carrier means for rotation therewith and mounted on the same for movement between an inoperative position and an operating position; a plurality of moving members pivotably mounted on said carrier means for rotation therewith and being pivotable in radial direction with respect to the axis of rotation of said carrier means from an inner position through an intermediate position to an outer end position, said moving members being respectively operatively connected with said needle-influencing elements for successively moving the same to said operating position thereof; cam means fixedly mounted on said support means and located adjacent said carrier means, said cam means including a first arcuate cam and a second arcuate cam, said first and second cams defining a gap between each other, said movable members sliding along said first cam during rotation of said carrier means and being held by the same in said inner position when arriving at said gap and then sliding along said second cam, said second cam having an inner arcuate cam surface for engaging said moving members in said inner position, and an outer arcuate cam surface having a first face portion adjacent said gap for engaging movable members in said intermediate position and a second face portion for guiding moving members to said outer end position so that the respective correlated needle-influencing elements are moved to the operating positions thereof; electromagnetic means located adjacent said gap, said electromagnetic means including a first electromagnet located inwardly of said gap and of said inner cam surface and a second electromagnet located outwardly of said gap and of said outer cam surface, said second electromagnet being selectively energized to attract selected moving members for moving the same through said gap to said intermediate position, and said first electromagnet being selectively energized to attract non-selected moving members to hold the same in said inner position until the same have passed beyond the gap and onto said inner cam surface so that the selected moving members are engaged by said outer

cam surface and moved to said outer end position while non-selected moving members are engaged by said inner cam surface and remain in said inner position; and return cam means disposed on said support means in the region of said first cam for engaging needle-influencing elements in said operating positions and for moving the same to said inoperative position before said needle-influencing elements and the respective correlated moving elements arrive at said gap during rotation of said carrier means.

7. In a patterning arrangement for a circular knitting machine, in combination, support means; carrier means rotatably carried by said support means; a plurality of needle-influencing elements carried by said carrier means for rotation therewith and mounted on the same for movement between an inoperative position and an operating position; a plurality of moving members movably carried by said carrier means for rotation therewith and respectively operatively connected with said needle-influencing elements for successively moving the same to said operating position thereof when said moving members are moved with respect to said carrier means; cam means fixedly mounted on said support means and located adjacent said carrier means for moving selected moving members during rotation of said carrier means with respect to the latter so as to move the correlated needle-influencing elements to the operating positions thereof; and electromagnetic means located adjacent said carrier means for selecting the moving members which are to be moved by said cam means.

8. A patterning arrangement as set forth in claim 7, wherein said electromagnetic means selects moving members by effecting movement of the same from an initial position to an intermediate position in which the selected moving members are engaged by said cam means, said cam means having a rising cam surface for moving the selected moving members farther to an end position whereby the respective needle-influencing elements are moved to said operating position.

9. A patterning arrangement as set forth in claim 7, wherein said cam means has a circular portion following said rising cam surface in the direction of rotation of said carrier means for rigidly holding the selected moving members in said end position and thereby said needle-influencing elements in said operating position.

10. A patterning arrangement as set forth in claim 9, wherein said cam means has an arcuate surface engaging on-selected moving members in said initial position for holding the same in said initial position during rotation of said carrier means.

11. A patterning arrangement as set forth in claim 9, wherein said cam means includes another cam portion, said other cam portion engaging during rotation of said carrier means the selected moving members in said end position for moving the same to said initial position before completion of a revolution by said carrier means.

12. A patterning arrangement as set forth in claim 7, wherein said cam means includes a first cam portion and a second cam portion defining a gap between each other; and wherein said electromagnetic means is located opposite said gap along the path of movement of said moving members and selects moving members by causing movement of moving members passing said gap through said gap, said first cam portion having a rising cam surface adjacent said gap for moving selected moving members having passed through said gap to an end position for shifting the correlated needle-influencing elements to said operating position.

13. In a patterning arrangement for circular knitting machines and the like, in combination, support means; carrier means rotatably carried by said support means; a plurality of springy members fixed to said carrier means for rotation therewith and respectively having free end portions; cam means acting on said free end portions of said springy members during rotation of said carrier

means for tensioning said free end portions, said cam means being formed with a gap through which said free end portions move; an electromagnetic means located adjacent said gap along the path of movement of said free end portions of said springy members for acting on said free end portions to prevent the latter from moving through said gap when said electromagnetic means is energized; and a plurality of jacks respectively located in the path of movement of said free end portions when the latter move through said gap to be moved by said springy members from inoperative positions respectively toward operating positions, whereby by selectively energizing said electromagnetical means selected jacks may be moved toward their operating positions.

14. A patterning arrangement as set forth in claim 13 wherein said cam means include a cam portion located on one side of said gap for tensioning said springy members, and a rising cam surface located on the other side of said gap for engaging said free end portions of the springy members which have past through said gap during rotation of said carrier means, said rising cam surface moving said free end portions to a position in which the correlated jacks are in said operating position.

15. In a patterning arrangement for circular knitting machines and the like, in combination, support means; carrier means turnably carried by said support means for rotation on said support means, said carrier means turning during each rotation past an operating station and a selecting station; a plurality of needle-influencing elements movably carried by said carrier means for rotation therewith and for movement with respect thereto between inoperative and operating positions; control means including electromagnetic means located at said selecting station for controlling the movement of selected needle-influencing elements toward their operating positions so that when the selected needle-influencing elements reach the operating station they will influence a needle at said operating station; and return cam means acting on the selected needle-influencing elements while they turn with said carrier means during each rotation thereof from said operating station to said selecting station to return the selected elements from their operating to their inoperative positions so that a new selection may be made as all of the elements move by the selecting station.

16. A patterning arrangement as set forth in claim 15 and including a set of movable members on said carrier means and respectively located adjacent said needle-influencing elements for controlling movement of the same to said operating positions; and wherein said electromagnetic means control the movement of selected movable elements and thereby the movement of said needle-influencing elements to said operating position.

17. A patterning arrangement as set forth in claim 16 and including cam means for holding selected movable members during rotation of said carrier means in a position in which the correlated needle-influencing elements are in said operating position while adapted to pass through an operating station.

18. In a patterning arrangement for circular knitting machines or the like, in combination, support means; carrier means rotatably carried by said support means; a plurality of springy members carried by said carrier means for rotation therewith, said springy members respectively having springy free end portions; cam means located adjacent said carrier means and acting on said free end portions of said springy members during rotation of said carrier means, said cam means having a gap and tensioning said free end portions of said members during rotation of said carrier means as said free end portions approach said gap so that the tensioned free end por-

tion will move through said gap during rotation of said carrier means; electromagnetic means cooperating with said cam means for selectively closing and opening said gap so that only selected free end portions of said springy members will pass through said gap; and needle-influencing jacks movably arranged on said carrier means so as to be movable between inoperative operating positions, said jacks being respectively located in the path of movement of said free end portions when the latter move through said gap so that the selected free end portions will move selected jacks when the selected free end portions move through said gap, said springy members when their free end portions move through said gap moving said jackets from their inoperative positions respectively toward their operating positions.

19. In a patterning arrangement for circular knitting machines and the like, in combination, support means; carrier means rotatably carried by said support means; a plurality of springy members carried by said carrier means for rotation therewith, said springy members respectively having springy free end portions; cam means carried by said support means adjacent said carrier means and being formed with a gap, said cam means engaging and tensioning said free end portions as the latter approach said gap so that said free end portions will move through said gap when the latter is open; a blocking lever pivotally carried by said support means for turning movement through a relatively small angle between a position where a free end of said lever closes said gap and an open position where said free end of said lever is spaced from said gap to open the latter; means operatively connected to said lever for turning the same between its positions whereby in accordance with the position of said lever selected free end portions of said springy members will move through said gap; and a plurality of needle-influencing jacks movably carried by said carrier means for movement between inoperative and operative positions, said jacks being respectively located in the path of movement of said free end portions of said springy members as said free end portions move through said gap, so that those free end portions of said springy members which move through said gap will engage and move selected jacks toward their operating position.

20. In a patterning arrangement for circular knitting machines and the like, in combination, support means; carrier means rotatably carried by said support means; a plurality of needle-influencing jacks movably carried by said carrier means for movement between inoperative and operating positions, respectively; a plurality of jack-moving members pivotally carried by said carrier means for rotation therewith and respectively located next to said jacks for moving the same toward their operating positions when said members are turned in a predetermined direction; and a pair of electromagnets operating counter to each other and located at a selecting station through which said jack-moving members move during rotation of said carrier means, one of said electromagnets turning said members when said one electromagnet is energized in a direction which moves the jacks respectively co-operating with the turned members toward their operating positions, respectively, and the other of said electromagnets when it is energized preventing the turning of said jack-moving members in a direction which moves said jacks toward their operating positions, so that the energizing and deenergizing of said electromagnets will cause selected jacks to move toward their operating positions.
